LUMINESCENT ATTACHMENT FOR TELEPHONE-HANDSET HANDLES

Ellis F. Nelson, Everett, Mass., assignor to E. F. Nelson Company, Inc., Boston, Mass., a corporation of Massachusetts

Application September 22, 1948, Serial No. 50,605

4 Claims. (Cl. 179—178)

1

The present invention relates to telephone equipment, and more particularly to accessories for telephone-handset handles.

An object of the present invention is to provide a new and improved telephone-handset handle.

Another object is to provide a new and improved receiver cap or mouthpiece cap for a telephone-handset handle.

Another object is to provide a new and improved cover for the receiver cap or the mouthpiece cap of a telephone-handset handle.

A further object is to provide a new and improved cover for the receiver cap or the mouthpiece cap of a telephone-handset handle which may be easily applied to and removed from the receiver cap or the mouth-piece cap.

Another object of the present invention is to provide new and improved means for illuminating the handset handle in order to render it visible in the dark.

A further object is to provide new and improved means for illuminating the receiver cap or the mouthpiece cap of a telephone-handset handle.

Still another object of the present invention is to provide a new and improved cover for the receiver cap or the mouthpiece cap of a telephone-handset handle that shall be luminescent to permit the receiver cap or the mouthpiece cap to be visible in the dark.

Other and further objects will be explained hereinafter and will be more particularly pointed out in the appended claims.

The invention will now be described more fully in connection with the accompanying drawings, in which Fig. 1 is a perspective of a present-day conventional telephone-handset handle, the receiver cap and the mouthpiece cap of which are provided with covers embodying the present invention; Fig. 2 is a similar perspective illustrating covers embodying the present invention, mounted upon the receiver cap and the mouthpiece cap of another present-day conventional telephone-handset handle; Fig. 3 is a plan, upon a larger scale than in Figs. 1 and 2, of a receiver-cap cover or a mouthpiece-cap cover constructed in accordance with the present invention; Fig. 4 is a side elevation of the same, looking toward the left, partly in transverse section, shown applied to the receiver cap of a telephone-handset handle, illustrated by dotted lines; Fig. 5 is a section, upon a still larger scale, taken upon the line 5—5 of Fig. 4, looking in the direction of the arrows; Fig. 6 is a section simi-

2

lar to Fig. 5 of a modification; Fig. 7 is a fragmentary transverse section similar to Fig. 4, upon a larger scale still, of a modified cover constructed in accordance with the present invention, but provided with a larger number of recesses in which luminescent material may be disposed; Fig. 8 is a similarly enlarged fragmentary transverse section of a further modified cover constituted, instead of metal, of a plastic material combined with a luminescent material in the plastic, and provided with a recess in which a metal or other decorative inlay may be inserted; Figs. 9, 10 and 11 are similarly enlarged fragmentary transverse sections of still further modified covers provided with recesses in which luminescent material may be disposed; Fig. 12 is a section similar to Figs. 7 to 11 illustrating a preferred embodiment of the present invention; Fig. 13 is a similar section of a modified cover provided with strips of plastic combined with luminescent materials in the plastic; Fig. 14 is a similar section illustrating an all-metal cover; Fig. 15 is a fragmentary perspective, partly in transverse section, upon a similarly enlarged scale, of a strip of plastic combined with luminescent materials in the plastic for application to some of the covers of the present invention; Fig. 16 is a fragmentary transverse section, upon a somewhat smaller scale than in Figs. 7 to 15, of a modified cover provided with a strip of luminescent material covered with a transparent plastic or other shell; Fig. 17 is a fragmentary transverse section similar to Figs. 7 to 14 of a modified cover having end portions of plastic material combined with a luminescent material; Fig. 18 is a plan similar to Fig. 3, illustrating a cover constructed in accordance with the present invention constituted wholly of a plastic material; Fig. 19 is an elevation of the same similar to Fig. 4, partly in section taken upon the lines 19—19 of Fig. 18, looking in the direction of the arrows; Fig. 20 is a fragmentary transverse section similar to Figs. 7 to 14 and 17, upon the same scale, illustrating a modified cover provided with a recess in which luminescent material may be disposed and provided with a covering layer, as of transparent plastic, for sealing the luminescent material; Fig. 21 is a similar fragmentary transverse section of still another modified cover; and Fig. 22 is a similar fragmentary transverse section of still a further modification.

In addition to the telephone cradles, not shown, present-day telephones comprise handset-telephone handles 1 or 10 upon one end of each of which is threadedly mounted a receiver cap 3

or 13 and upon the other end of each of which is threadedly mounted a mouthpiece cap 5 or 15. The receiver caps 3 and 13 and the mouthpiece caps 5 and 15 are each exteriorly provided circumferentially with a rounded surface 2 of more or less cylindrical or slightly tapering or conical construction, and their outer end walls are convex, as shown at 4. Though shown by full lines in Figs. 1 and 2, they are illustrated by dashed lines in Figs. 7 to 14, 17, 21 and 22, in order not to distract from the essential features of novelty of the present invention. As appears clearly from these dashed-line showings of Figs. 7 to 14, 17, 21 and 22, after the receiver cap 3 or 13 or the mouthpiece cap 5 or 15 has been threaded upon the corresponding end of the handset handle 1 or 10, the separation between the inner or left-hand circularly shaped end of each cap and the said end of the handset handle 1 or 10 is marked by a peripherally disposed groove 43. Another peripherally disposed groove 31 is integrally formed in each receiver cap 3 and 13 and each mouthpiece cap 5 and 15 near the outer or right-hand circularly shaped end of the cap.

In accordance with a feature of the present invention, a collar-shaped cover member is provided for detachably encircling each receiver cap 3 or 13, and a similar collar-shaped cover member is provided for detachably encircling each mouthpiece cap 5 or 15. The collar-shaped member 7 is shown encircling the receiver cap 3, the collar-shaped cover member 17 the receiver cap 13, the collar-shaped cover member 9 the mouthpiece cap 5 and the collar-shaped cover member 19 the mouthpiece cap 15.

The collar-shaped cover member 7 is shown provided at its inner circularly shaped end 35 with an abruptly bent terminal peripheral flange 33 projecting inwardly toward the center of the collar-shaped cover member 7. The function of the flange 33 is to hook into the peripherally disposed groove 43. By reason of this engagement of the flange 33 with one or more walls of the groove 43, the cover member 7 becomes locked to the receiver cap 3, so as to prevent its becoming accidentally detached during use of the telephone-handset handle 1. Though shown projecting from the circularly shaped end throughout the complete 360 degrees of the circle, it is not essential, of course, that the flange 33 be of so large extent; it will perform its locking function even if very much smaller.

The collar-shaped cover member 7 may similarly be provided at its outer circularly shaped end 25 with another abruptly bent terminal peripheral flange 23, projecting inwardly, like the terminal peripheral flange 33, toward the center of the collar-shaped cover member 7. As shown, for example, in Figs. 7, 9, 12, 14 and 22, this additional terminal peripheral flange 23 may hook into the peripherally disposed groove 31, thereby serving additionally to hold the cover 7 upon the cap 3, 5, 13 or 15. The outer circularly shaped end 25 of the collar-shaped cover 7 may, however, be unprovided with the additional terminal peripheral flange 23. It may be wholly unflanged, so as to extend beyond the peripheral groove 31 of the receiver cap 3, as shown in Figs. 4, 8, 10, 11 and 13. If desired, indeed, the end 25 of the collar-shaped member 7 may extend further outward beyond the groove 31 than as shown in Figs. 4, 8, 10, 11 and 13, so as to provide a gradually tapering terminal peripheral flange 22, as shown in Fig. 21. The gradually tapering terminal peripheral flange 22 of Fig. 21 may engage snugly 75 the outer convex end walls of the receiver cap 3 or 13 or the mouthpiece cap to help hold the cover member 7 upon the receiver or mouthpiece cap without the use of the abruptly bent terminal flange 23 for hooking into the recess 31.

The collar-shaped receiver-cap covers 7 and 17 and the collar-shaped mouthpiece-cap covers 9 and 19 may be continuous, as illustrated in Figs. 18 and 19, or they may be split, as illustrated in Figs. 3 and 4. In order to mount the continuous covers upon the receiver caps 3 and 13 or the mouthpiece caps 5 and 15, it is necessary either that these caps be first unscrewed from their telephone-handset handles 1 and 10, or that the continuous covers be sufficiently stretchable or expansible to permit their mounting upon the receiver caps 3 and 13 or the mouthpiece caps 5 and 15 without such previous unscrewing. If the collar-shaped covers 7, 9, 17 and 19 are split, however, it is merely necessary that they be constituted of some material that is sufficiently resilient to expand without stretching. With the employment of such a material, the ends of the split collar-shaped cover may be resiliently separated or sprung apart at the split to open the collar. This permits of conveniently and easily either removing the detachable split collar-shaped cover 7 or 17 from the receiver cap 3 or 13, respectively, or the detachable split collar-shaped cover 9 or 19 from the mouthpiece cap 5 or 15, respectively. Upon the reapplication of the split collar-shaped cover to its cap, it will snap back into its normal shape, to engage the exterior rounded surface 2 of the cap 3, 5, 13 or 15, with the flange 23 in the groove 31 and, if desired, the flange 23 in the groove 43 and, if desired, the flange 23 in the groove 31, to lock the cover snugly and tightly in position on the receiver cap 3 or 13 or the mouthpiece cap 5 or 15.

The cover of the present invention may be 40 manufactured from any suitable flexible or resilient metal or plastic. As an example of a metal, spherodized carbon steel 0.018 inch thick has been found admirably suited to the purpose. As examples of suitable plastics, reference may be 45 made to the vinyl resins, the styrene compounds, the phenolic compounds, the urea-base compounds, the cellulose acetates and other cellulose products, and the methyl-methacrylate resins. These plastics may be suitably plasticized to 50 render them of the proper flexibility or resiliency.

As shown at 31, the split collars 7, 9, 17 and 19 may be split transversely, as illustrated in Figs. 3, 4 and 5, or at an incline, such as 45 degrees, as 55 illustrated in Fig. 6. In either event, the ends of each split collar 7, 9, 17 or 19 will snap back into abutting contact with each other after the collar has been mounted over the cap 3, 5, 13 or 15 upon which it is mounted. The inclined arrangement illustrated in Fig. 6, however, provides 60 for overlapping of the ends of the split collar, as well. If the material of which the collars is constituted is sufficiently resilient, the collars will be held snugly and tightly in place through the inherent resiliency alone of the material of which the collars is constituted, without the necessity for providing any additional means to hold the collars in place upon their caps. Additional locking mechanisms, such as tongue-and-groove connections, may, however, be provided, if desired.

As illustrated in Figs. 4, 7 to 11 and 13, the collar-shaped covers 7, 9, 17 and 19 may be shaped to conform closely to the rounded exterior surfaces 2 of the receiver caps 3 and 13 or the mouthpiece caps 5 and 15. The shapes of the

covers 7, 9, 17 and 19 may be such, however, that they will be intermediately separated from the surfaces 2 of the caps, as illustrated in Figs. 12, 14, 17, 21 and 22, being held in place merely by the terminal peripheral flanges 33 and 23 in the respective peripherally disposed grooves 43 and 31.

According to a further feature of the invention, the receiver caps 3 and 13 and the mouthpiece caps 5 and 15 and, therefore, the handset handles 1 and 10, as well, are rendered visible in the dark by illuminating the collars 7, 9, 17 and 19. This illumination is preferably effected through the use of some self-luminescent material, as with the aid of phosphorescence, fluorescence or radium emanation.

Many radioactive salts are available for this purpose. Among the luminescent phosphors that may be employed, for example, are zinc sulphides, zinc and cadmium sulphides, and cadmium and strontium sulphides, with or without traces of radioactive substances, such as radium, or other auto-activated phosphors containing radioactive material that will glow in the dark. As is well known, phosphorescent materials, for example, will glow as the result of the excitation to which they may be subjected by the natural light of day, or the artificial light of incandescent, fluorescent or other lamps prior to their extinguishment, or by invisible rays, as of ultraviolet. Cadmium and strontium sulfides, for example, may glow for a long time in the dark in response to but a few minutes of excitation by daylight or artificial light. If the material is chemically treated with a radium compound, of course, it will glow at all times, day and night, but this glow will naturally become enhanced in the dark. If the phosphor is combined with a radioactive substance, the phosphor will be illuminated in the dark as a result of the excitation produced by the radioactive substance. The luminescent material may be applied, bodily, in the form of paints or pigments, by decalcomania processes, and in other ways.

According to the embodiment of the invention illustrated in Figs. 1 and 4, two circular strips 11 of such luminescent material are shown peripherally disposed symmetrically in the form of two parallel rings throughout the circumference of the exterior rounded surface of each collar-shaped cover 7 mounted upon the receiver cap 3 and the collar-shaped cover 9 mounted upon the mouthpiece cap 5. Two similar strips 21 of such luminescent material are shown peripherally disposed symmetrically in the form of two parallel rings throughout the circumference of the exterior rounded surface of each collar-shaped cover 17 mounted upon the receiver cap 13 and the collar-shaped cover 19 mounted upon the mouthpiece cap 15.

When the telephone-handset handle 1 or 10 occupies its resting position on the telephone cradle, not shown, therefore, not only do the covers 7, 9, 17 and 19 provide attractive ornaments for the telephone-handset handles 1 and 10, but also the self-luminescent strips 11 or 21, particularly in the dark, present two pairs of glowing rings symmetrically disposed with respect to the handle 1 or 10 that may be easily observed and reached in the dark. To enhance the ornamental effect, furthermore, decorative designs may be provided in the portions of the area of the cylindrical or slightly tapering exterior surface between the parallel luminescent circular strips 11 or 21 of each collar-shaped cover 7, 9, 17 or 19. This area,

indeed, is sufficiently large to provide not only for decorative ornamentation, but also, if desired, for other purposes such as for advertising. The strips 11 or 21 may also themselves be constituted of a decorative material, such as a suitably decorative plastic. Such plastic material may be physically or chemically combined, or both, with the luminescent material in a manner well known in the art, in order both to provide for luminescence in the dark and to present either the pleasing colors or the transparency of the plastic when viewed in the light. In order that it may not crack during the opening and closing of the split collars 7, or during the stretching or other expansion of the continuous collars 7, this plastic is preferably flexible or resilient. A transparent polystyrene resin in combination with a luminescent pigment comprising cadmium and strontium sulfides, for example, provides a useful combination of this character.

The receiver-cap covers 7 and 9 and the mouthpiece-cap covers 17 and 19 may all be substantially alike. It will not, therefore, be necessary to describe more than one of these covers. Several of the numerous different forms that the covers 7, 9, 17 and 19 may assume are accordingly illustrated in Figs. 3 to 22 in connection with the receiver-cap cover 7.

According to the embodiment of the invention illustrated in Fig. 4, the luminescent strips 11 are shown set into two parallel symmetrically disposed peripheral recesses 29 provided in the round surface of the cover 7, throughout the circumference thereof. It is not, of course, essential that the luminescent material be inserted in the recesses 29. It may, for example, be applied to an unrecessed exterior rounded surface of the cover 7 bodily, or in the form of a coating of phosphorescent or other self-luminescent pigment or paint; it may be applied by pasting to the unrecessed exterior rounded surface a paper layer carrying the phosphorescent material; and it may be applied also in many other ways. It is preferred to insert the luminescent material in the recesses 29, however, because this protects it against being rubbed away.

According to the preferred embodiment of the invention that is illustrated in Fig. 12, the cylindrical or tapering wall of the collar-shaped member 7 is bent along two parallel circumferential lines to provide two parallel ring-like peripherally disposed ribs 39 and 41. The recesses in which the luminescent strips 11 may be inserted are provided at the outer surfaces of these ribs 39 and 41 within the ribbing. With the aid of the ribbing structure, the recesses may be rendered deeper than as illustrated in Fig. 4. In addition to thus providing deeper recesses for holding the luminescent material, moreover, the ribs 39 and 41 also increase the structural rigidity for the member 7.

The number of peripherally disposed ribs 39 and 41, the number of circumferential recesses formed thereby, and the number of strips 11 disposed in the recess may be increased, as shown at 45 in Fig. 7. As shown in Fig. 8, on the other hand, the number of strips may be decreased to one.

The strips 11 need not, moreover, be limited in thickness to that provided for by the increased depth afforded by the increased depth of the recesses furnished by the ribbed structure. As shown in Fig. 9, the relatively thin strips 11 of Fig. 7 or Fig. 12 may be replaced by strips 11 of larger cross-dimension. These may be press-

fitted into the recesses provided by the ribbed structure 39. Undercut walls may be provided in these recesses to aid the action of holding the strips; or the strips 11 may be held in place by adhesives or other mechanical means. Because of their larger cross-dimension, these press-fitted strips 11 may extend substantially beyond the exterior surface of the collar-shaped member 7, thus enabling them to gather more light during the periods of exposure to the light, and thereby to luminesce for a longer period in the dark.

According to the modification illustrated in Fig. 13, the collar-shaped member 7 is crimped at 51, and the crimped regions are provided with strip coverings 11 of the combined plastic and luminescent material. A similar structure, but without the crimped regions 51, is illustrated in Fig. 22, according to which the strip covering 11 is applied along the circumferentially disposed annular crown of a cover member 7 that is intermediately bulged out to form the crown.

It is not essential, of course, that the luminescent material be applied in the form of one or more strips 11. The luminescent material may be applied also in other ways. It may even be scattered throughout the area of the cover 7. The flexible or the resilient collar-shaped member 7 may, indeed, be wholly constituted of a single piece of the preferably resilient plastic material before described, physically or chemically combined with the luminescent material. As illustrated in Fig. 8, however, this single piece of plastic may be ornamented by providing it with one or more recesses 47 of the same nature as either of the recesses 29, into which a decorative metal or other inlay strip 63 may be press-fitted or otherwise inserted.

The arrangement of the plastic and the metal illustrated in Fig. 8 may, however, be interchanged. As illustrated in Fig. 10, the resilient cover 7 may be of metal, and it may be provided with one or more recesses 47 in which strips 11 of the combined plastic and luminescent material may be inserted.

The recesses 47 may, however, be omitted. A resilient all-metal collar-shaped cover member 7, without any additional luminescent material is illustrated in Fig. 14. It is shown integrally provided at its respective ends 25 and 35 with the respective flanges 23 and 33 for locking in the respective recesses 31 and 43. In all but extremely dark rooms, this all-metal collar, if highly polished, will reflect sufficient light to render it at least faintly visible, even in the absence of luminescent material.

According to the embodiment of the invention that is illustrated in Fig. 17, the resilient metal cover 7 may be provided with end portions 61 of combined plastic and luminescent material. These end portions 61 may be shaped to provide projections for hooking into the peripheral grooves 31 and 43, in order to lock the member 7 upon the receiver or mouth-piece cap.

Instead of the all-metal cover 7 of Fig. 14, on the other hand, the cover 7 may be constituted of solid plastic, as illustrated in Figs. 18 and 19. If the plastic is light-colored, it may be at least faintly seen in all but very dark rooms, as in the case of the all-metal cover 7 of Fig. 14, even in the absence of luminescent material.

According to the modification of the invention that is illustrated in Fig. 11, a metal collar-shaped member 7 is provided with apertures 49 into which buttons of combined plastic-and-luminescent material 55 may be press-fitted. Instead of the

buttons, plugs 55 projecting integrally from a strip of combined plastic-and-luminescent material 53, as illustrated in Fig. 15, may be inserted in the apertures 49 in order to secure the strip 53 to the member 7.

Where the luminescent material for application to the collar-shaped member is provided with a trace of radioactive substance, such as radium, there would be danger that the radioactive substance might come into contact with the user. In order to render the radioactive substance innocuous, therefore, a transparent plastic or other shell 59, as shown in Fig. 16, may be employed to cover the luminescent material. A similar transparent covering layer 65 is shown in Fig. 20 sealing a luminescent layer 11 in the recess 47 of the member 7.

Further modifications will occur to persons skilled in the art, and all such are considered to fall within the spirit and scope of the present invention, as defined in the appended claims.

What is claimed is:

1. In a telephone provided with a telephone-handset-handle upon an end of which an exteriorly round-surfaced receiver cap or mouth-piece cap is mounted with a peripherally disposed groove disposed between the cap and the said end of the handle, a cover for the cap comprising a split collar-shaped resilient member for encircling the cap along its exterior round surface provided with luminescent material having a terminal flange projecting inwardly from an end of the collar-shaped resilient member adapted to be received in the groove to hold the cover on the cap, the ends of the split collar-shaped resilient member being adapted to be separated at the split to open the collar-shaped resilient member in order to permit of applying the cover to the cap and to remove the cover from the cap.

2. In a telephone provided with a telephone-handset handle upon an end of which an exteriorly round-surfaced receiver cap or mouth-piece cap is mounted with a first peripherally disposed groove disposed between the cap and the said end of the handle and a second peripherally disposed groove, a cover for the cap comprising a collar-shaped resilient member for encircling its exterior round surface provided with a luminescent material having a first terminal flange projecting inwardly from one end of the resilient member adapted to be received in the first groove and a second terminal flange projecting inwardly from the other end of the collar-shaped resilient member adapted to be received in the second groove to hold the cover on the cap.

3. In a telephone provided with a telephone-handset handle upon an end of which an exteriorly round-surfaced receiver cap or mouth-piece cap is mounted with a first peripherally disposed groove disposed between the cap and the said end of the handle and a second peripherally disposed groove, a cover for the cap comprising a collar-shaped member for encircling its exterior round surface having a first terminal flange projecting inwardly from one end of the collar-shaped resilient member adapted to be received in the first groove and a second terminal flange projecting inwardly from the other end of the collar-shaped resilient member adapted to be received in the second groove to hold the cover on the cap, the collar-shaped resilient member being provided with peripherally dis-

posed ribbings providing recesses containing luminescent material.

4. In a telephone provided with a telephone-handset handle upon an end of which an exteriorly round-surfaced receiver cap or mouth-piece cap is mounted with a first peripherally disposed groove disposed between the cap and the said end of the handle and a second peripherally disposed groove, a cover for the cap comprising a split collar-shaped resilient member for encircling its exterior round surface having a first terminal flange projecting inwardly from one end of the collar-shaped resilient member adapted to be received in the first groove and a second terminal flange projecting inwardly from the other end of the collar-shaped resilient member adapted to be received in the second groove to hold the cover on the cap, the ends of the split collar-shaped resilient member being adapted to be separated at the split to open the split collar-shaped resilient member in order to permit of applying the cover to the cap and to remove the cover from the cap, and the collar-shaped resilient member being provided with peripherally disposed ribbings providing recesses containing combined plastic-and-phosphorescent material.
